THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

SHEET-METAL END STRUCTURE FOR RAILWAY-CARS.

1,332,857.

Specification of Letters Patent.

Patented Mar. 2, 1920.

Application filed October 13, 1919. Serial No. 330,299.

To all whom it may concern:

Be it known that I, THOMAS NATHAN RUSSELL, a citizen of the United States, residing in Chicago, in the county of Cook and State of Illinois, have invented a new and useful Improvement in Sheet-Metal End Structures for Railway-Cars, of which the following is a specification.

This invention relates to end structures for railway cars, and has for its essential object the provision of a corrugated sheet metal end structure of maximum strength and that affords a maximum resistance to the severe shocks and stresses to which car end structures are necessarily subjected. The invention also includes among its objects such other advantages and results as may be found to obtain in the structures hereinafter set forth or claimed.

In the accompanying drawings, forming a part of this specification and showing, for purposes of exemplification, a preferred form and manner in which the invention may be embodied and practised, but without limiting the claimed invention specifically to such illustrative instance or instances:

Figure 1 is an end elevation of a railway box car provided with a corrugated sheet metal end constructed in accordance with the present invention.

Fig. 2 is a vertical sectional elevation of the same on the line 2—2 of Fig. 1.

Fig. 3 is a fragmentary side elevation of that portion of the railway box car adjacent to the end of the car.

Fig. 4 is a composite horizontal sectional view on the line 4—4 of Fig. 1.

Fig. 5 is an enlarged detailed diagrammatic view of a metallic plate having corrugations of ordinary type.

Fig. 6 is an enlarged sectional view of a metallic plate having corrugations constructed in accordance with the present invention.

The same characters of reference indicate the same parts throughout the several views.

Referring to the drawing, the railway box car embodies in its construction the usual sides 21—21, vertical corner posts 22—22, end sheathing 23, roof 24, flooring 25 and end sill 26.

In accordance with the invention, the

end sheathing 23 of the car comprises an upper metallic sheet 27 and a lower metallic sheet 28, the upper metallic sheet overlapping the lower metallic sheet, as shown at 29, and secured thereto by a line of rivets 30. The two sheets 27—28 are secured to the corner posts 22 of a car by lines of bolts 31—32, said lines of bolts being respectively located near the sides of the car; and the sheets 27—28 are preferably formed with flanges 33—34 at their opposite vertical edges which are bent over said posts of the car and respectively secured thereto by lines of bolts 35—36. The end plate 37 adjacent the roof of the car overlaps the upper sheet 27 of the car end, as shown, and is secured thereto by rivets 38. The bottom edge of the lower sheet 28 may be secured to the end sill 26 by a horizontal line of rivets 39.

As shown in the drawings, the upper sheet 27 is formed with a plurality of parallel horizontal corrugations extending thereacross and merging into the flat margins of the sheet, to which are applied the vertical lines of bolts 31—32 and constituting a symmetrically corrugated main body of the sheet; and the lower sheet 28 is formed with a plurality of similarly formed horizontal corrugations which, however, are relatively deeper than the corrugations of the upper sheet 27. The end sheathing 23 is secured to the horizontal nailing strips 42—43 by series of bolts 40—41 passed through the nailing strips and the corrugated portion of the upper sheet 27 and likewise to nailing strips 46—47 by series of bolts 44—45 passed through said nailing strips and the corrugated portion of the lower sheet 28. As the resistance to stress of a corrugated sheet of metal increases uniformly with the depth of the corrugations, the corrugations of the lower sheet 28 of the end wall of a car are made relatively deeper than those of the upper sheet, for the reason that the lower sheet is required to withstand much greater thrusts and heavier pressures than the upper sheet, including the thrusts and pressures produced by shifting of the load within the car of which the greater force is brought to bear on the lower sheet.

With this construction the end wall of the car is made particularly strong at the points where it is required to bear the heaviest shocks.

An important feature of the invention

lies in the particular formation of the corrugations in the sheets 27-28 constituting the end of a railway car. These corrugations are especially constructed to secure a maximum strength and resistance to pressures and thrusts in the sheet forming the car end. With this end in view, the corrugations of an end sheet are formed in such manner that as large a proportion of metal as possible is located above and below the neutral axis of the sheet, *i.e.* the horizontal line through a section of the sheet which will be neither stretched or compressed under stresses or loads applied to the sheet. As the resistance of a corrugated sheet of metal to stretching or compressing forces increases uniformly as the distance from the neutral axis increases either above or below the neutral axis, the sheet is greatly strengthened by the crowding of as much metal as possible in the hills and valleys of the corrugations, which are respectively above and below the neutral axis, and, as shown in the drawings, the flat tops 48, 49 of the truncated corrugations are of substantial width but not wider than the depth between such tops of the corrugations disposed on opposite sides of the neutral plane of the sheet body. With this construction, metal is massed at the greatest distance from the neutral plane of the sheet-body, so as to secure the full strengthening effect mentioned above, without extending the flat tops of the corrugations to such a width that they are beyond the range of the truss effect of the sloping webs connecting them. In this manner and by this construction, there is obtained a new and improved arrangement and disposition of the metal which is available in the sheet, so as to produce a sheet of maximum stiffness and resistance against bending inwardly or outwardly; that is to say, as much metal is disposed at the maximum distance from the neutral plane of the sheet, as is consistent with the necessary frequency of its supports, which are the inclined connecting web portions. In other words, if the inclined supports are not frequent enough the shape of a flat uncorrugated sheet is approached, with a resultant decreased stiffness; on the other hand, if the supports are too frequent, as where the opposite inclined portions meet to form edges or apices, there is no extended disposition of metal at the greatest distance from the neutral plane, so that an important factor of strength is lost. The corrugated sheet provided by the present invention is of maximum stiffness and strength because it combines the two strength contributing factors in a corrugated sheet in the most advantageous way, namely: the inclined supports are frequent enough to obtain the greatest possible number of corrugations while at the same time the flat tops are of

such extended width as to secure a disposition of the greatest possible mass of metal at the greatest distance from the neutral plane of the sheet.

In the form of the invention illustrated in Figs. 1 to 4 inclusive, the corrugated sheets of the car end are made of great strength by forming such sheets with truncated corrugations, the flat tops of which may be respectively disposed to constitute flat hills 48 and flat valleys 49. The portions 50 connecting the hills 48 with the valleys 49 may likewise be flat as shown. The much greater strength of a metal sheet corrugated in the manner above specified is illustrated by the comparison given in Figs. 5 and 6, in which Fig. 5 represents diagrammatically an ordinary corrugated sheet having rounded hills and valleys, and Fig. 6 represents a corrugated sheet formed with flat hills and valleys. Assuming that line A-B indicates the neutral axis of the two sheets shown in Figs. 5 and 6: it will be readily perceived that the sheet indicated in Fig. 6 contains more metal of maximum stress resisting property than the sheet indicated in Fig. 5. This is because of the fact that only the tips 51 of the hills and valleys of the rounded corrugations of the plate of Fig. 5 are located at the greatest distance above and below the neutral axis A-B, whereas in the corrugated plate illustrated in Fig. 6 the flattened hills 48 and flattened valleys 49 constitute broad surfaces of metal that are located the maximum distance above and below the neutral axis A-B. As the strength of the metal of the plate increases uniformly with its distance from the neutral axis, it follows that the corrugated plate illustrated in Fig. 6 and constructed in accordance with the invention is of much greater strength and has much higher resistance to pressures and shocks than the ordinary plate of Fig. 5.

The feature of having the upper and lower sheets differ from each other in the depth of their respective corrugations, irrespectively of the form of the corrugations, is the subject of my application Serial No. 356,292, filed February 4, 1920, as a division of this application.

The invention, as hereinabove set forth, is embodied in a particular form of construction, but may be variously embodied within the scope of the claims hereinafter made.

I claim:

1. A sheet metal end structure for railway cars embodying: an upper metallic sheet secured to the frame of a car and formed with horizontal parallel corrugations having substantially flat hills and valleys; and a lower metallic sheet also secured to the frame of the car and formed with horizontal parallel corrugations, relatively deeper than the corrugations of said upper

sheet and having substantially flat hills and valleys; substantially as specified.

2. A sheet metal end structure for railway cars, embodying: an upper metallic sheet secured to the frame of a car and formed with horizontal parallel corrugations having substantially flat hills; and a lower metallic sheet also secured to the frame of the car and formed with horizontal corrugations, relatively deeper than the corrugations of said upper sheet and having substantially flat hills; substantially as specified.

3. A sheet metal end structure for railway cars, embodying: an upper metallic sheet secured to the frame of a car and formed with horizontal parallel corrugations having substantially flat valleys; and a lower metallic sheet also secured to the frame of the car and formed with horizontal parallel corrugations, relatively deeper than the corrugations of said upper sheet and having substantially flat valleys; substantially as specified.

4. A sheet metal end structure for railway cars, embodying: an upper metallic sheet secured to the frame of a car and formed with horizontal parallel corrugations of which the hills, valleys, and connecting portions between the hills and valleys are substantially flat; and a lower metallic sheet also secured to the frame of the car and formed with horizontal parallel corrugations relatively deeper than the corrugations of said upper sheet, of which the hills, valleys, and connecting portions between the hills and valleys are substantially flat; substantially as specified.

5. A sheet metal end structure for railway cars, embodying: an upper metallic sheet secured to the frame of the car and formed with flattened horizontal parallel corrugations; and a lower metallic sheet also secured to the frame of the car and formed with flattened horizontal parallel corrugations relatively deeper than the corrugations of said upper sheet; substantially as specified.

6. A sheet metal end structure for railway cars, embodying: an upper metallic sheet body secured to the car frame and constituted of a plurality of parallel corrugations merging at their ends in to the margins of the sheet, said corrugations being formed with extended flat tops joined by sloping webs, the width of such flat tops being not greater than the depth between the tops of

corrugations disposed on opposite sides of the neutral plane of the sheet body; and a lower metallic sheet body also secured to the car frame and constituted of a plurality of corrugations formed similarly to but relatively deeper than those of the upper sheet body, to resist the relatively greater load-thrust developed in the lower portion of the car; substantially as specified. 60 65

7. A metallic end-sheet for railway cars embodying a sheet-body constituted of a plurality of truncated parallel corrugations merging at their ends into the margins of the sheet and having their flat tops joined and trussed by sloping webs, the flat tops being of substantial width but not wider than the depth between such tops of the corrugations disposed on opposite sides of the neutral plane of the sheet body, whereby 70 75 metal is massed at the greatest distance from said neutral plane but not extended beyond the range of the truss effect of said webs, substantially as specified.

8. A metal-end sheet for railway cars embodying a sheet-body constituted of a plurality of truncated parallel corrugations having their flat tops joined and trussed by sloping webs, the flat tops being of substantial width but not wider than the depth between such tops of the corrugations disposed on opposite sides of the neutral plane of the sheet-body, whereby the metal is massed at the greatest distance from said neutral plane but not extended beyond the range of the 80 85 90 truss effect of said webs, substantially as specified.

9. A sheet-metal car-end embodying a sheet-body constituted of a series of parallel corrugations pressed alternately inwardly 95 and outwardly from the neutral plane of the sheet-body, said corrugations being formed with flat tops each of which is of an extended width not greater than the total depth of the sheet-body perpendicularly 100 through its neutral plane, said flat tops being connected by inclined webs longer than said tops, substantially as specified.

10. A corrugated metal sheet for railway car-walls, having its body constituted of 105 parallel truncated corrugations whose oppositely presented flat faces are of less extended width than the connecting webs that truss them, as described.

In testimony whereof I have hereunto set 110 my hand this 9th day of October, 1919.

THOMAS NATHAN RUSSELL.
